UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,816, dated October 29, 1895.

Application filed September 27, 1895. Serial No. 563,930. Term of patent 3½ years.

To all whom it may concern:

- Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.
- 10 The design consists of a series of ornaments of the Empire style of design placed at regular distances apart over the surface of the paper, as represented in the accompanying drawing.
- 15 The border for said design consists of similar shaped ornaments of the Empire style of design inclosed in ornamental-oval shaped wreaths with a light oval-shaped band of ornaments inside of said wreaths and torch-like ornaments connecting said wreaths by 20 bands of ribbon, as shown in the drawing.

What I claim is—

1. The design for wall paper herein shown and described.
2. In the design for wall paper, the border 25 herein shown and described.

Witness my hand this 24th day of September, 1895.

CHARLES BOOZ.
